UNITED STATES PATENT OFFICE.

CLIFTON D. PETTIS, OF NEW YORK, N. Y.

METHOD OF HOLDING EXPANDED-METAL OR SIMILAR BRAKE-SHOE INSERTS.

Application filed April 11, 1924. Serial No. 705,779.

To all whom it may concern:

Be it known that I, CLIFTON D. PETTIS, a citizen of the United States, residing in New York city, in the county and State of

5 New York, have invented certain new and useful Improvements in Methods of Holding Expanded-Metal or Similar Brake-Shoe Inserts, of which the following is a specification.

10 This invention relates to the manufacture of brake shoes but more particularly to methods of holding expanded metal or other inserts in the mold during the molding operation, and has for its primary object to prevent the insert from floating or becoming displaced within the mold cavity, when the melted metal is poured.

15 It is common practice to incorporate in the casting a bundle of strips of expanded metal and these have generally been bound together by wires passing through the openings in the metal. This bundle or mattress is then placed in the mold and the metal poured in the usual manner. No satisfactory means has heretofore been employed to prevent the bundle from floating or becoming displaced when the melted metal enters the mold cavity, so far as I am aware. This destroys the effectiveness of the expanded metal which should be at the face of the shoe. To obviate this, I have devised a method of positioning the insert within the mold.

20 The many other objects and advantages of my invention will be better understood by reference to the following specification when considered in connection with the accompanying drawing illustrating certain selected embodiments thereof, in which:

25 Fig. 1 is a side elevation of a brake shoe insert prepared for insertion into the mold cavity.

30 Fig. 2 is a transverse section on the line 2-2 of Fig. 1, and

35 Fig. 3 is a transverse section similar to Fig. 2, of an optional form of positioning means.

40 Referring to the drawing, the brake shoe insert 10 comprises a bundle or mattress of strips, here six in number, of expanded metal. These strips are held together by

looped wires 11 and 12 preferably near the ends of the bundle. As each of these loops is the same in construction, only one will be described.

45 The wire 11 is preferably inserted through the openings in the expanded metal from the face 12 of the bundle toward the back. It is then twisted together as at 13 and the ends bent outwardly as at 14, 14: 60 This wire is preferably in the shape of a hairpin when it is inserted in the bundle.

55 In the form shown in Fig. 3, the bent out ends 15 of the wire are slightly longer than in the form illustrated in Fig. 2, and are 65 bent down as at 16 to fit snugly between the side walls of the reinforcing back or shell 17.

60 The height from the face of the bundle to the top of the portion of the wire forming the bent out ends 14 or 15 determines the 70 spacing of this face from the opposite surface of the cast metal body.

65 The height from the face of the bundle to the top of the portion of the wire forming the bent out ends 14 or 15 determines the 75 spacing of this face from the opposite surface of the cast metal body. The closing of the mold then causes these wires to act as slightly 80 compressed springs which force the insert against the mold wall.

70 While my improved method is particularly adapted for use in molds where the walls are hard and will not permit the projecting wires to penetrate therein, it is fully 85 applicable to soft sand molds where these wires will act against some hard body such as the reinforcing back or shell being incorporated in a railway brake shoe.

75 The form shown in Fig. 3 has the additional advantage of accurately locating the bundle transversely with respect to a reinforcing shell but this is not usually necessary as the location of the bundle transversely can be generally determined with sufficient accuracy by the eye. It is obvious 80 that this transverse positioning may be accomplished without bending down the ends of the wires provided the lateral spread corresponds to the inside dimensions of the shell. The insert and shell are placed in the

mold in the usual manner. The outline of the finished casting is indicated in dot, Fig. 3.

An insert of any kind provided with positioning means functioning in the manner described cannot float in the mold or become displaced during the casting operation. The form of this positioning means is immaterial so long as it effectively performs this function and it should be distinctly understood that the particular types herein shown and described are for illustration only, as I am aware that the same result may be obtained from an indefinite number of different forms which will readily occur to any one skilled in the art.

I claim as my invention:

1. The method of preparing a multi-part metal insert for placing within a casting mold, which consists in tying together the parts of the insert and forming on the tying means one or more members projecting from the insert a distance equal to the proper spacing of the insert from the corresponding surface of the cast metal body.

2. The method of preparing a multi-part metal insert for placing within a casting mold, which consists in tying together the parts of the insert with wire and forming on the tying wire a member which projects from a face of the insert substantially a distance equal to the proper spacing of that face from the opposing wall of the mold cavity.

3. The method of preparing an insert made up of a bundle of super-imposed strips of foraminous metal for placing within a casting mold, which consists in inserting through the openings in the under face of the bundle the free ends of a substantially U-shaped wire and twisting together the end portions of the wire above the bundle to tightly bind the parts of the insert and form on the upper face of the insert a member projecting upwardly therefrom a distance equal to the proper spacing of this face from the opposing wall of the mold cavity.

4. The method of preparing an insert composed of a bundle of super-imposed strips of foraminous metal for placing within a mold cavity, which consists in pressing through the openings in the under face of the bundle the free ends of a substantially U-shaped wire, twisting together the portions of the wire above the bundle to tightly bind the parts and form a member projecting upwardly from the top face of the insert a distance equal to the proper spacing of this face from the opposing face of the mold wall, bending the free ends of the wire transversely of the bundle in opposite directions, said bent ends forming with the upwardly projecting member a substantially T-shaped part.

5. The method of preparing a metal insert for insertion in a casting mold which consists in attaching upon the upper face of the insert at longitudinally spaced points substantially T-shaped members which project upwardly from said face a distance equal to the proper spacing of this face from the top wall of the mold cavity.

6. The method of preparing an insert for placing in a casting mold which consists in attaching upon one face of the insert at longitudinally spaced points substantially T-shaped members which project from said face sufficiently to maintain this face at the proper spacing from the opposing wall of the mold cavity, the cross arms of the T in each of said members being formed of sufficient length to co-act with the mold walls adjacent said opposing wall to prevent lateral movement of the insert in the cavity.

7. The combination with an insert to be embedded in a casting, of means for positioning the insert in the mold cavity during the casting operation comprising a length of wire enveloping a portion of the insert and having portions thereof projecting from said insert sufficiently to maintain the insert at the proper spacing from the corresponding walls of the mold cavity.

8. The combination with an insert to be embedded in a casting, of means for positioning the insert in the mold cavity during the casting operation comprising a wire loop enveloping a portion of the insert with the free end portions of the wire twisted together and projecting from a face of the insert a distance equal to the proper spacing of this face from the opposing wall of the mold cavity.

9. The combination with an insert to be embedded in a casting, of means for positioning the insert in the mold cavity during the casting operation comprising a length of wire enveloping a portion of the insert, and the free end portions of said wire being twisted together to securely attach the wire to the insert, said end portions projecting from the face of the insert sufficiently to maintain said face at the proper distance from the opposing wall of the mold cavity.

10. The combination with a multi-part insert to be embedded in a casting, of means for tying together the parts of the insert and properly positioning the insert in the mold cavity during the casting operation, comprising a loop of wire enveloping portions of the parts of the insert and the free end portions of the loop twisted together, said end portions being caused to project from the face of the insert sufficiently to maintain said face at the proper interval from the opposing wall of the mold cavity.

11. The combination with a multi-part

insert to be embedded in a casting, of means for tying together parts of the insert and properly positioning said insert in the mold cavity during the casting operation, comprising a length of wire looped about portions of the parts of the insert and having the free end portions of the wire twisted

together to cause the wire to tightly bind said parts, said end portions projecting from the insert sufficiently to maintain the insert at the proper spacing from the wall of said cavity.

CLIFTON D. PETTIS.
